UNITED STATES PATENT OFFICE

172,313

PENCIL OR SIMILAR ARTICLE

William C. Rucker, Shelbyville, Tenn., assignor to Commonwealth Cedar Company, Inc., doing business as Cavalier Pencil Company, Shelbyville, Tenn., a corporation of Tennessee

Application September 18, 1953, Serial No. 26,862

Term of patent 7 years

(Cl. D74—24)

To all whom it may concern:

Be it known that I, William C. Rucker, a citizen of the United States, residing at Shelbyville, Tennessee, have invented a new, original, and ornamental Design for a Pencil or Similar Article, of which the following is a specification, reference being had to the accompanying drawing, forming a part thereof.

Fig. 1 is an elevational view of a pencil or similar article, showing my new design;

Fig. 2 is a bottom plan view;

Fig. 3 is a cross sectional view thereof taken on the line 3—3 of Fig. 1.

I claim:

The ornamental design for a pencil or similar article, substantially as shown.
